UNITED STATES PATENT OFFICE

WILLIAM E. LAURA, OF SAN JOSE, CALIFORNIA

DESIGN FOR A WINDSHIELD BRACKET

Application filed January 20, 1930. Serial No. 34,188. Term of patent 3½ years.

To all whom it may concern:

Be it known that I, WILLIAM E. LAURA, a citizen of the United States, residing at San Jose, in the county of Santa Clara and State of California, have invented a new, original, and ornamental Design for Wind Shield Brackets, of which the following is a specification, reference being had to the accompanying drawings, forming part thereof.

Figure 1 is a side elevational view of a windshield bracket showing my new design;

Figure 2 is an end elevation thereof, and Figure 3 is a top plan view thereof.

The design consists essentially in the features of providing the downwardly curved and depending portion shown in the upper left hand portion of Figure 1 and the laterally extending flange extended from the beaded portion of the wind shield bracket.

I claim:

The ornamental design for a wind shield bracket, as shown and described.

WILLIAM E. LAURA.
